UNITED STATES PATENT OFFICE.

OLIVER J. HELVEY, OF BUFFALO, NEW YORK.

REFLECTOR.

1,408,597.

Specification of Letters Patent.

Patented Mar. 7, 1922.

Application filed January 10, 1920. Serial No. 350,611.

To all whom it may concern:

Be it known that I, OLIVER J. HELVEY, a citizen of the United States, residing in Buffalo, in the county of Erie and State of New York, have invented new and useful Improvements in Reflectors, of which the following is a specification.

This invention relates to a reflector which is more particularly intended for illuminating show cases although the same may also be employed to advantage for lighting windows and blackboards.

The purpose of this invention is to produce an efficient and durable reflector of this character which is low in manufacturing cost and is composed of comparatively few parts which can be readily assembled and dismembered, and which is neat and attractive in appearance.

20 In the accompanying drawings:

Figure 1 is a perspective view of the reflector embodying my improvements. Figure 2 is a longitudinal section of the same taken on line 2—2, Fig. 1. Figure 3 is a cross section taken on line 3—3, Fig. 2. Figure 4 is a fragmentary cross sectional view of the body and the lamp supporting bar showing the form of the same preparatory to assembling the same. Figures 5 and 30 6 are detached perspective views of the body and one of the heads of the same. Figure 7 is a fragmentary vertical section of a glass show case showing one of the brackets for supporting the reflector on the case. Figure 35 8 is a perspective view of the bracket before the same is applied to the reflector and mounted on the show case.

Similar characters of reference refer to like parts throughout the several views.

40 The body 10 of this reflector is preferably constructed of a single sheet of metal which is bent by any suitable means into substantially U-shaped form in cross section, its side walls being curved so that the front parts 11 of the same are comparatively far apart and form a wide front longitudinal space within the body while the rear parts 12 of these walls are arranged comparatively close together and form a narrow or reduced 45 rear longitudinal channel 13 within the body, this reduced space being closed at the back by the rear wall 14 of the body.

50 At opposite ends of the body are arranged two heads each of which consists of a transverse plate 15 which is of the same form as the cross section of the body and engages

with the edge of the body at one end thereof and a flange projecting inwardly from the edge of the plate and having two forwardly diverging curved side portions 16 and front 60 and rear portions 17, 18 arranged substantially perpendicular to the curved parts of the flange and connecting the front and rear parts of the latter. The curved side portions 16 of the flange of each head engage 65 with the outer sides of the curved side walls of the body at one end thereof, the front parts 17 extends across the space between the front edges of the body side walls and the rear portion 18 engages with the outer 70 side of the back wall of the body. Each of these heads is preferably constructed of sheet metal and the same is slipped on one end of the body and held there in any suitable manner. These heads are preferably 75 detachably connected with the body for convenience in assembling and dismembering the reflector, replacement, inspection or cleaning and this is accomplished in a simple and efficient manner by providing the front 80 parts of the body side walls adjacent to the ends thereof with indentations or recesses 19 which receive inwardly extending projections or teats 20 formed on the inner sides of the curved side portions of the head 85 flanges at the front ends thereof. The interlocking of these recesses and projections is effected by springing the parts carrying the same over each other and a separation of the same is effected in like manner, the 90 metal being sufficiently resilient for this purpose.

In order to retain the front edges of the side walls of the body in a distended position each of the front parts 17 of the head 95 flange is provided with inwardly projecting retaining beads or projections 21 each of which engages with the inner side of one of the body walls adjacent to one of its front corners and thereby retains the same firmly 100 in engagement with one of the front corners of the respective head.

Within the channel in the back of the body is arranged a supporting bar 22 upon which is mounted the electric lamp 23 which 105 latter is arranged lengthwise in the body. This supporting bar is preferably constructed of U-shaped form in cross section of sheet metal and placed in the reduced channel in the rear of the body so that the 110 concave side of this bar faces backwardly or toward the concave side of the body. For

the purpose of retaining this bar in the body without requiring any special fastening to accomplish this, the side parts 12 of the channel are so constructed that they converge forwardly and the side parts 24 of the supporting bar are also constructed to converge forwardly relatively to the front wall 25 thereof, so that when the body and bar are assembled the side walls of the body 10 will press inwardly against the side walls of the bar whereby the latter will be firmly gripped and interlocked with the body to prevent these parts from becoming detached. To obtain this result the walls of the body 15 are initially spread apart beyond the normal position which they occupy when assembled and the side walls of the bar are also spread apart an abnormal extent. When thereafter the side walls of the body are drawn in- 20 wardly against opposite sides of the walls of the bar these members are reliably held in place after the heads or caps are applied to the body.

The lamp is supported on the bar by securing its base in one end of a tubular angle socket 26 the opposite end of which is secured in an opening in the front wall 24 of the supporting bar at one end thereof so that the interior of the angle socket 25 communicates with the conduit formed between the opposing concave sides of the supporting bar and body. On the exterior of one of the heads of the body is arranged an inlet nipple 27 which is secured at one end 30 in an opening in said head so that this nipple communicates with the conduit between the bar, body and heads. The electric conducting wires 28 extend through this nipple conduit and angle socket for supplying the lamp with current.

The reflector may be supported on the show case, in the window on a blackboard or elsewhere by any suitable means.

As an instance of the use of this reflector 45 the same is shown in Fig. 7 mounted in an oblique position in one of the upper inner corners of a glass show case having an upright transparent front wall 29 and a horizontal upper wall 30.

50 A bracket suitable for supporting the reflector in this case comprises a U-shaped yoke having an angular seat 31 which engages with the exterior of the contracted rear part or back of the body and two trans- 55 verse arms 32, 33, projecting forwardly from opposite ends of said seat along opposite outer sides of the body and provided at their front ends with inwardly turned hooks 34 which engage with the opposite 60 front edges of the body, and a supporting arm 35 arranged in the slit between the upper edge of the vertical wall and the underside of the top wall and having a re- 65 versely bent lip 36 at its front end which is secured by a loop 37 to the upper arm of

the yoke while its rear end is provided with a downwardly turned lip 38 which engages with the outer side of said vertical wall. The yoke is preferably made of a single strip of metal and the supporting arm is 70 made of another strip of metal which are bent into suitable shape to fit the reflector and the show case and these two members are connected with each other by the loop which is preferably soldered thereto. 75

In its complete form this reflector is strong and durable, attractive in appearance and will effectively distribute the light of the lamp particularly when the inner surface of the body and the bar are nickel 80 plated and polished to form a high reflecting surface.

I claim as my invention:

1. A reflector having an integral body which is substantially U-shaped in cross section and provided in its rear part with a reduced longitudinal channel, and a lamp supporting bar of U-shaped form in cross section arranged lengthwise in said channel and having its concave side facing inwardly, the opposing side walls of said bar diverging backwardly and the opposing side walls of said channel converging forwardly and engaging with the outer side of the opposing walls of said supporting bar for 95 retaining the latter in place.

2. A reflector comprising a longitudinal body of substantially U-shaped form in cross section, and heads arranged on opposite ends of said body, each head having a transverse plate engaging with an end edge of the body and a flange on said plate engaging with the outer side of an end portion of the body, said flange and the adjacent part of said body being provided with 100 co-operating projections and recesses.

3. A reflector comprising a longitudinal body of substantially U-shaped form in cross section, and heads arranged on opposite ends of said body, each head having a transverse plate engaging with an end edge of the body and a flange on said plate engaging with the outer side of an end portion of the body, the front part of the flange of each head which extends across the space 110 between the side walls of the body being arranged substantially perpendicular to those parts of this flange which engage with the outer sides of the side walls of said body, and said front part of the flange being provided with internal projections between which and the adjacent side flange portions the side walls of said body are confined.

4. A reflector comprising a longitudinal body of substantially U-shaped form in cross section, and heads arranged on opposite ends of said body, each head having a transverse plate engaging with an end edge of the body and a flange on said plate en-

gaging with the outer side of an end portion of the body, the front part of the flange of each head which extends across the space between the side walls of the body being arranged substantially perpendicular to those parts of this flange which engage with the outer sides of the side walls of said body, and said front part of the flange being provided with internal projections between which and the adjacent side flange 10 portions the side walls of said body are confined, and the side walls of said body and the corresponding side portions of the head flanges being provided with interlocking projections and recesses.

OLIVER J. HELVEY.
